UNITED STATES PATENT OFFICE.

WENDELL L. NICHOLS, OF BOSTON, MASSACHUSETTS.

DESIGN FOR A BODY FOR MOTOR-VEHICLES.

No. 38,436.

Specification for Design.

Patented Jan. 29, 1907.

Application filed December 26, 1906. Serial No. 349,585. Term of patent 14 years.

To all whom it may concern:

Be it known that I, WENDELL L. NICHOLS, a citizen of the United States, residing at Boston, in the county of Suffolk and State of Massachusetts, have invented a new, original, and ornamental Design for Bodies of Motor-Vehicles, of which the following is a specification, reference being had to the accompanying drawing, forming part thereof.

The figure is a side elevation of the body of the vehicle, showing my new design.

I claim—

The ornamental design for a body for motor-vehicles, as shown.

WENDELL L. NICHOLS.
